[57] CLAIM

The ornamental design for an expandible sealing plug for pipelines and the like, as shown and described.

DESCRIPTION

FIG. 1 is an isometric view taken from the front and side of an expandible sealing plug for pipelines and the like showing my new design;

FIG. 2 is an isometric view taken from the rear and side thereof;

FIG. 3 is an isometric view taken from the front and side of a modified form of the expandible sealing plug for pipelines and the like shown in FIGS. 1 and 2; and

FIG. 4 is an isometric view taken from the rear and side of FIG. 3.

FIG. 1.

FIG. 2.

FIG. 3.

FIG. 4.
